A. Ade Rommelle

UNITED STATES PATENT OFFICE.

JACOB A. ONDRAK, OF BROOKLYN, NEW YORK.

SKELETON GIRDLE OR BELT.

1,279,141.

Specification of Letters Patent. Patented Sept. 17, 1918.

Application filed September 9, 1916. Serial No. 119,201.

To all whom it may concern:

Be it known that I, JACOB A. ONDRAK, a citizen of the United States, and resident of Brooklyn, in the county of Kings and State of New York, have invented certain new and useful Improvements in Skeleton Girdles or Belts, of which the following is a specification.

This invention relates to a skeleton girdle or belt. One of its objects is the production of a girdle or belt that can easily be adjusted to the body of the wearer with a uniform pressure throughout its surface. Means are provided for supporting a garment when located adjacent to the outer face of said girdle. It also has an abdominal supporting attachment, which extends from the lower portion of the girdle. The organization of the invention principally comprises a pair of members that coact with each other to produce a girdle adjustable to different sizes. The girdle comprises essentially two members, each of which consists of a pair or more of straps that terminate in a single strap. The single strap of one member adjustably coacts with the pair or more straps of the other member. The front ends of the members are always in the same relative positions with respect to each other and the adjustments are made by locating the rear middle portions of each member in different positions.

In the drawings Figure 1, represents an inside elevation of an exemplification of the girdle or belt, Fig. 2, is a top plan view of Fig. 1; Fig. 3 shows an outside elevation of the front of the girdle or belt in place on a wearer; Fig. 4 is an enlarged fragmentary portion of Fig. 1 with a fragmentary portion of a garment; Fig. 5 is a section of Fig. 4 on the line 5, 5; Fig. 5^a shows a section as on the line 5^a 5^a of Fig. 4; Fig. 5^b shows a fragmentary portion of Fig. 5 with a modification; Fig. 6 represents a view similar to Fig. 1 with a modification and Fig. 7 shows a view similar to Fig. 1 with a further modification.

Referring to Figs. 1 to 5^a, the girdle or belt is shown to comprise a pair of main members 20 and 55.

The member 20 consists of the pair of outer straps 21, 22, and the pair of inner straps 23, 24. The strap 21 preferably converges at its outer end. The two pairs of straps 21, 22, and 23, 24 at their outer ends are connected to a tab 25, which converges

at its outer edge and at the lower portion thereof. The two pairs of straps converge at their inner ends where they form the single strap 30. The tab 25 has embedded therein the eyelets 31, and the single strap 30 has connected thereto a hook 32 on the outer face thereof.

The pair of straps 21, 22 and 23, 24 are connected to the guide braces 36 to 40. The 65 guide braces 36, 37 and 38 each comprise a resilient strip of material 40, preferably of spring steel, which is covered by a fibrous covering 41. Stitching 42 and 43 connects the members of the covering 41 and holds 70 the ends of the strip 40 in place. The stitching is omitted at the central portions of the covering 41, to form a guide opening 44, the function of which will be presently described. The upper and lower ends 75 of the guide braces 36 to 38 are within the two members *a* and *b* of the strap 21 and between the member *c* and *d* of the strap 22.

The tab 25 extends below the strap 22 and supplemental straps 46 and 47 connect 80 the lower portion of the tab 25 and the strap 22 and constitute an abdominal attachment. The guide braces 39 and 40 are essentially similar to 36, 37, and 38, with the exception that they pass between the members *c* and *d* 85 of the strap 22 and extend to and are fastened to the outer faces of the straps 46 and 47.

Through the member *a* of the strap 21, the covering 41 and the strip 40 is secured 90 a fastener with the head 48 and the flexible shank 48^a. The shank is spread after passing through the inner portion of the covering 41 to hold the fastener in place. Stitching 49 in the strap 21 provides a 95 pocket 50 for the ends of the shanks of the fastener, and prevents said fastener coming in contact with the wearer when the girdle or belt is in use. A garment in this case a pair of trousers 52 is detachably supported on the said fastener, the heads 48 being located on the outside of the garment. 100

The member 55 of the girdle comprises the pair of straps 56, 57, similar to 21, 22 and the pair of straps 58, 59, similar to 23, 105 24. The latter two pairs of straps converge into the single strap 60, similar to 30, and which has connected thereto a number of eyelets 61. A tab 65 similar to 25 and reinforced with a resilient strip of material 110 connects the outer ends of the two pairs of straps 56, 57 and 58, 59. The tab 65 ex-

tends below the straps 57, and supplemental straps 66, 67, respectively similar to 46 and 47 connect the lower portion of the tab 65 and the strap 57, and constitutes an abdominal attachment. Hooks 70 on the outer face of the tab 65 are properly located to connect with the eyelets 31 of the tab 25, when the girdle or belt is in place upon the wearer. The strap 56 also has fasteners 48 connected thereto as described for the strap 21. Guide braces 76, 77, 78, 79 and 80 respectively similar to 36 to 40 connect the pairs of straps 56, 57 and 58, 59. Two of said guide braces 79 and 80 are connected with the supplemental straps 66 and 67, bearing against the outer facings of the latter as described for the braces 39 and 40.

In the modification shown in Fig. 6 a girdle or belt is represented which is similar to that already described except that a pair of the straps of each member are omitted. The girdle or belt in this case comprises the members 85 and 95. The member 85 comprises a single pair of straps 86, 87 similar respectively to 21, 22 and which converge into the single strap 88, similar to 30 with its hook 32. The member 95 comprises the pair of straps 89, 90 respectively similar to 56, 57. The straps 89, 90 converge into the single strap 91 similar to 60 with its eyelets 61. Guide braces 36 to 40 as already described connect the strap 86 and 87 and guide braces 76 to 80 as already described connect the straps 89 and 90. The tabs 25 and 65 respectively connect the ends of the pair of straps 86, 87, and 89, 90. The tab 25 is shown with its eyelets 31 and tab 65 is shown with its hooks 70. Supplemental straps 46, 47, 66 and 67 as already described and constituting an abdominal attachment are shown in Fig. 6.

In Fig. 7 a girdle or belt is shown similar to that represented in Fig. 6, with the exception that the supplemental straps 46, 47, 66 and 67 are omitted. It is shown to comprise the members 100 and 125 respectively similar to 85 and 95. The member 100 is comprised of a pair of straps 101, 102 similar respectively to 86, 87, and which terminate in the single strap 103 similar to 88. The member 125 is comprised of a pair of straps 106, 107 which terminate in the single strap 108. The straps 100, 102 at their outer ends are connected by the tab 115 and the straps 106, 107 are connected at their outer ends by the tab 116. Eyelets 117 are provided for the tab 115 and hooks 118 are secured to the tab 116. Eyelets 119 are provided for the strap 108 and a hook 120 extends from the strap 103. Guide braces 36 to 38 as already described and similar guide braces 39, 40 connect the straps of the member 100 and guide braces 76, 77, 78 as already described and similar guide braces 79^a and 80^a connect the straps of the member 125. When the

girdle belt is in use and referring particularly to Figs. 1 to 5^a, the hooks 70 of the tab 65 engage the eyelets 31 of the tab 25, and the hook 32 of the strap 30 engages any of the eyelets 61 of the strap 60. Thereby 70 the girdle can be made to conform to the contour of the body of the user, the strap 30 being slidable in the guide braces 76 to 80 of the member 55, and the strap 60 being slidable in the guide braces 36 to 40 of the member 20. The girdle can be changed in size making it smaller or larger to suit the user by separating or bringing together the guide braces 36 and 76 and maintaining the tabs 25 and 65 in the normal positions as 80 shown particularly in Fig. 3.

The straps 46, 47 and 66, 67, support the abdomen, and always remain in the same position. When the girdle or belt is adjusted to various sizes the straps 30 and 60 85 are used to make the adjustments. The number of straps like 21, 22, 23, 24 of a member of the girdle or belt may be increased.

The style of the fasteners having the 90 heads 48 may be changed. A fastener like the one shown in Fig. 5^b may be used and which consists of the head 125, shank 126 and bottom disk 127.

Having described my invention what I 95 desire to secure by Letters Patent and claim is:—

1. In a girdle the combination of a pair of members, each member comprising a number of straps terminating in a single strap, 100 means in each member to slidably guide the single strap of the other member and supplemental straps for each member to form an abdominal support.

2. In a girdle the combination of a pair 105 of members, each member comprising a number of straps terminating in a single strap, means in each member to slidably guide the single strap of the other member, means to support a garment, tabs on the ends of the 110 members and supplemental straps connecting each tab with one of the straps of the number of straps of each member to form an abdominal support.

3. In a girdle the combination of a pair 115 of members, each member comprising a pair of straps terminating in a single strap, means in each member to slidably guide the single strap of the other member, pockets formed in one of the straps of each pair of 120 straps, fasteners extending through the latter straps with one end of each protected in one of said pockets, the said fasteners adapted to support a garment and supplemental straps for the lower one of each pair 125 of straps to constitute an abdominal attachment.

4. In a girdle the combination of a pair of members, each member comprising a number of straps terminating in a single 130

strap, a tab connecting the ends of each of said number of straps, means to connect the tabs to each other, means to connect the ends of the single straps to each other at different points to vary the length of the girdle or belt, fasteners extending from one of each of the straps of the number of straps to support a garment, and an abdominal attachment extending from each of the members.

5. In a girdle the combination of a pair of members, each member comprising straps terminating in a single strap, means in each member to slidably guide the single strap of

the other member, pockets formed in one 15 of the straps of each member and fasteners each with a head and a flexible shank extending through the latter straps, the flexible shanks spread at their ends and located in said pockets, the said fasteners adapted to 20 support a garment.

Signed at the borough of Manhattan in the county of New York and State of New York this 7th day of September A. D. 1916.
